Primary Examiner — Karen S Acker*Assistant Examiner* — Clare Ann Gannon(74) *Attorney, Agent, or Firm* — Smartpat PLC; Axel Nix**CLAIM**

I claim the ornamental design for a substrate with camouflage pattern, as shown and described.

DESCRIPTION

The patent or application file contains at least one drawing executed in color. Copies of this patent or patent application publication with color drawing(s) will be provided by the Office upon request and payment of the necessary fee. The sole FIGURE is a plan view of a substrate with camouflage pattern showing my new design.
